UNITED STATES PATENT OFFICE.

ROBERT WILLIAM SMITH, OF FILEY, ENGLAND.

CANDLE HOLDER AND CANDLE.

Application filed January 7, 1927, Serial No. 159,661, and in Great Britain January 13, 1926.

This invention relates to candle holders and candles, and has for its chief object to provide a simple form of candle holder and candle therefor whereby the candle will be 5 efficiently supported in the holder in such a manner as to enable the said candle to be entirely consumed.

According to the invention, the candle is provided or formed at its lower end with a 10 series of outward projections adapted to pass between and engage beneath a series of inwardly projecting lugs or flanges formed on or associated with the upper end of the candle holder.

15 In order that the invention may be clearly understood and readily carried into effect, the same will now be more fully described with the aid of the accompanying drawings in which:—

20 Figures 1 and 2 are elevation and plan respectively of a candle according to the invention.

Figures 3 and 4 are similar views to Figures 1 and 2 respectively showing the candle 25 and candle holder therefor.

Figure 5 is a vertical section taken on line 6—6 of Figure 4 the candle holder in this view being slightly modified as hereinafter described.

30 Referring now to the drawings, *a* is the candle and *b* the candle holder. As shown the candle *a* is formed with an enlarged lower end adapted to afford three outwardly and radially projecting portions *c* equally 35 spaced apart around its periphery, and the upper end of the candle holder *b* is provided with a cup-shaped member *d* which is provided or formed around its upper edge or rim with three overturned and equally 40 spaced inwardly projecting flanges *e*; the arrangement being such that the candle may

be placed in the holder *b* by passing the candle-projections *c* between and past the inward projections of cup-shaped member *d*, and then turning the candle *a* about its longitudinal axis so as to cause the outward projections *c* of the candle to pass beneath and engage the inward projections *e* of the cup-shaped member provided on the upper end of the candle holder *b*. For the purpose of affording a better grip for the turning movement, the lower end of the candle above the lugs may be corrugated longitudinally. The base of the cup-like member *d* which may be either integral with or separate from the candle holder as shown in Figure 5, may be provided with a central aperture or depression at *f* through or into which an extension of the wick *g* of the candle *a* may be passed to retain the wick *g* in an 60 upright position till the candle has been entirely consumed.

I claim:

1. The combination of a candle holder having a candle receiving socket, three equally spaced lugs projecting inwardly above said socket, a candle having three equally spaced outwardly projecting lugs adapted to pass between and be turned beneath said holder lugs, and wick receiving means in the bottom wall of the socket to receive and maintain the candle wick in upright position.

2. The combination of a candle holder having a shallow cup-shaped candle receiving socket, three equally spaced lugs projecting inwardly from the periphery of the said socket, and a candle having three equally spaced lugs projecting outwardly from the lower end of the candle, said lugs adapted to pass between and be turned beneath said holder lugs.

ROBERT WILLIAM SMITH.
